UNITED STATES PATENT OFFICE.

MARY E. FOX, OF BALTIMORE, MARYLAND.

DESIGN FOR A SUPPORTER FOR INFANTS' DIAPERS.

SPECIFICATION forming part of Design No. 32,934, dated July 10, 1900.

Application filed April 14, 1900. Serial No. 12,943. Term of patent 14 years.

To all whom it may concern:

Be it known that I, MARY E. FOX, of Baltimore, in the State of Maryland, have invented and produced a new and original Design for a Supporter for Infants' Diapers, of which the following is a specification, reference being had to the accompanying drawing, forming a part of the same.

The accompanying drawing is a representation in perspective of a supporter embodying the present design.

The characteristic features of the design are the downwardly-tapering body portions united at the top by shoulder-straps and depending tabs, with straps interposed between the tabs and narrow ends of the body portions.

In said drawing the letter A indicates a back, and B a front, body portion, both of the same

shape, tapering downwardly and at the upper ends united by straps C. A central aperture D is left between the upper edges of the body portions, and from this aperture a slit E extends downwardly into the front body portion, as shown. Straps E' form downward extensions of the body portions at both front and rear and at their ends merge into tabs F, also tapering downwardly and conforming generally to the shape of the body portions, so as to present a symmetrical appearance. 30

What I claim is—

The design for a supporter for infants' diapers herein described and shown.

MARY E. FOX.
